(57) CLAIM

We claim the ornamental design for a scooped cosmetics applicator, as shown and described.

DESCRIPTION

FIG. 1 is a top perspective view of the claimed design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is a right-side cross sectional elevation view thereof, taken along line 8-8 shown in FIG. 2.

The invention pertains to an ornamental design for a scooped cosmetics applicator. The solid lines represent the bounds of the claimed design, whereas those features shown in broken lines form no part of the claimed design. The features shown in broken lines include a ferrule and a handle, both shown in FIGS. 1-5 and 7-8.
